PUMP

**Knut Henrichsen, Los Angeles, Calif., assignor to
North American Aviation, Inc.**

Application November 26, 1948, Serial No. 62,024

13 Claims. (Cl. 103—162)

1

This invention relates to a pump or motor of the type described in patent application Serial No. 749,629 filed August 22, 1947, now Patent No. 2,604,856, in the name of Knut Henrichsen.

The invention more particularly relates to an improved pump of high efficiency and light weight.

It is therefore an object of this invention to provide a relatively small unit having high power output.

It is another object of this invention to provide a unit having novel features which decrease the friction, with a corresponding increase in efficiency.

It is still another object of this invention to provide in a hydraulic unit of this type novel features which obtain high power output for a design of relatively light weight.

It is yet another object of this invention to provide in a swash plate type pump a very great angle between the driving shaft and the driven shaft so as to obtain the maximum stroke.

It is a further object of this invention to provide in a unit of this type a valve which is floatingly mounted with respect to the cylinder block or cylinder assembly which normally operatively carries the same.

Other objects of invention will become apparent from the following description taken in connection with the accompanying drawings, in which

Fig. 1 is a sectional view of applicant's improved pump;

Fig. 2 is a sectional view along line 2—2 of Fig. 1;

Fig. 3 is a sectional view along line 3—3 of Fig. 1;

Fig. 4 is a sectional view of the cylinder bore and sleeve arrangement forming a part of this invention taken along the line 4—4 of Fig. 3;

Fig. 5 is a sectional view taken along line 5—5 of Fig. 1;

Fig. 6 is an elevational view partly in section showing an improved piston forming a part of this invention; and

Fig. 7 is a sectional view partly in elevation showing an improved bearing arrangement forming a part of this invention.

Referring to the drawings there is provided a housing 1 adapted to receive a drive member 2 suitably mounted therein by antifriction bearings 3 and 4. The drive member is connected by a pair of universal joints referred to generally as 5 and 6 to a combination axle hub and universal joint connection 7 which in turn is drivingly con-

2

nected by pin and slot arrangement 8 to a cylinder block 9 suitably rotatably mounted on axle 10 by antifriction bearings 11 and 12. A spring 13 operatively positioned between the axle and cylinder block urge the cylinder block and members carried thereby into operative sealing position in a manner to be hereinafter more fully described.

Operatively mounted within the cylinder block 10 in cylinder bores 14 are pistons 15 of particular design to be hereinafter more fully described. These pistons are connected by rods 16 and ball bearings 17 to drive-member 2 and are held in operative position with respect thereto by ball retainers 18, one retainer being provided for each ball. These retainers are L-shaped, with an opening for engaging the forward ends of the balls. They are held in place by pins 19 and springs 20 and are each installed by tilting the retainer against the action of the spring 20 associated therewith until a retaining pin 21 can be placed in an opening in pin 19. Springs 20 thereupon hold pins 19 with retaining pins 21 in snug relation with drive member 2. This spring and pin combination for operatively positioning the ball retainers 18 is so arranged that at low speeds only a small force such as that supplied through pins 19 and springs 20 is applied to the bearing surfaces between retainers 18 and ball bearings 17. This eliminates unnecessary wear and provides low friction at low speeds. However, as the rotative speed increases there is a greater tendency for ball bearings 17 to pull out of their sockets in drive member 2, requiring a greater retaining force. In the present arrangement this retaining force is automatically obtained with increased speed, resulting in centrifugal acceleration of the weight of the retainer itself. Thus, the force tending to pull the connecting rod balls out of their sockets increases as the square of the R. P. M. Likewise, the centrifugal force of the ball retainers 18 increases as the square of the R. P. M. This is accomplished in the present invention by having the ball retainers of such a preselected mass that the resulting action thereof on ball bearings 17 will serve to exert a force on the balls of sufficient amount, and in such a direction, that they will be retained in their bearing sockets. In this connection it is noted that the outer portion 22 of the sockets extends forwardly of the inner portion thereof in order to assist in providing such a reaction. As previously described in the specification and illustrated in Fig. 1 of the drawing, 55 L-shaped retainers 18 engage the forward por-

tion of ball bearings 17. When the pump rotates, the centrifugal force exerted by these retainers will urge them radially outward against ball portion 17. By engaging the forward portions of the balls, the retainers will, when urged outwardly by reason of their rotation, exert a force pushing the balls into the sockets in the general direction of overhanging portion 22. As the speed of rotation increases, the centrifugal force exerted by the retainers will likewise increase and will thus exert a greater force retaining the balls in the sockets.

Operatively connected to the forward portion of the cylinder block by gimbals 23, or other suitable universal connection, is a valve 24 having a bearing 25 on axle 10. Bearing 25 of course may be plain or antifriction, as desired, it being only necessary that the valve be floatingly mounted insofar as its connection with the cylinder block is concerned. The forward portions of the cylinder bores 14 are operatively connected to the valve by means of sleeves 26 and washers 27. The sleeve and washer arrangement functions to effectively seal the fluid flow through the forward end of bore 14 and valve port 28 into suitable ports 29 and 29a in valve block 30. Springs 31 urge the sleeves and washers into sealing engagement with valve 24 and urge the valve into engagement with valve block 30. From valve block 30 the fluid is transmitted through inlet and outlet ports 32 and 33 respectively to a device (not shown) to be actuated by the pump.

The combination of the valve carried by the cylinder block for floating movement with respect thereto permits self-aligning freedom in all directions at each cylinder. This allows the use of a considerably smaller valve diameter than heretofore, resulting in a substantial reduction of friction loss in the valve face.

Another feature of the invention which reduces friction, leakage, and wear, is a reduction in the diameter of the piston intermediate its ends. Referring now to Fig. 6 the external diameter of piston 16 is reduced intermediate its ends at 34 a small amount—in the neighborhood of a few ten-thousandths of an inch—for the purpose of obtaining desired fluid pressure distribution in the space between the piston and the cylinder wall. This tends to keep the piston centered with respect to the cylinder, with all the resultant advantages of such an arrangement.

Another friction reducing and balancing feature of the present invention comprises the fluid bearing arrangement as shown in Figs. 6 and 7. This feature involves providing piston 16 with an orifice 35 precalculated in area to obtain the results desired for the passage of fluid pressure through an opening 36 in the connecting rod and the connecting opening 37 in bearing 17 to an enlarged area 38 in that bearing for transmitting fluid pressure to take the thrust load of the connecting rod. The area 38 is of such a size as to properly take the thrust in the desired operating range of the pump. Such an arrangement is particularly desirable for reducing static friction in cases where the unit has to start as a motor under heavy load.

A further feature of the pump is the elimination of valve noises and power losses in the operation of the valve ports. Thus, inlet and outlet valve ports 32 and 33, respectively, are arranged so that the valve will close the individual cylinder port as the corresponding piston reaches the end of its stroke. This is accomplished in the arrangement of Fig. 5 by foreshortening the upper

end of valve port 29 and the lower end of port 29a. Thus the distance *a* from the centerline of the pump is less than *b*, and the distance *c* is less than *d*. With such an arrangement the fluid on the outlet side of the structure will be slightly compressed before the port is uncovered. Likewise, the opening of the inlet valve is delayed sufficiently long to permit the fluid to expand slightly before the valve is effectively opened. In the operation of the pump the delayed opening of the valve permits the fluid trapped between the piston and the valve at the beginning of the outlet stroke to be pressurized before the valve opens, so that the pressure is the same on both sides of the valve at the instant of opening. In a similar way, pressure is relieved from the fluid trapped between the piston and the valve at the beginning of the intake stroke. Without this increase and decrease of pressure the sudden equalization of pressures in the instant when the port opens would result in considerable power losses because of compressibility shocks, as well as in considerable noise, which would make the pump unsuitable for many purposes.

Although the invention has been described and illustrated in detail, it is to be clearly understood that the same is by way of illustration and example only and is not to be taken by way of limitation, the spirit and scope of this invention being limited only by the terms of the appended claims.

I claim:

1. A pump comprising a housing, a drive member and a cylinder block rotatably mounted in said housing, said cylinder block having bores therein, piston means reciprocably received within said bores, universal joint means connecting said drive member to said cylinder block, a valve block in said housing, said valve block having inlet and outlet ports therein, a valve member connector means securing said valve member to said cylinder block with freedom for universal movement relative thereto whereby said valve member is floatingly carried by said cylinder block for operatively connecting bores in said cylinder block with ports in said valve block, pistons in said bores, ball bearing means connecting said pistons to said drive member, said pistons and bearing means having an opening from the pressure side of said pistons to the pressure side of said bearing means for relieving pressure on said bearing means.

2. A device as recited in claim 1 and further including means for retaining said ball bearing means in said drive member, said retaining means comprising a ring positioned so as to engage the inner portion of said ball member remote from said drive member so that centrifugal force resulting from rotation thereof will exert a ball retaining force thereon.

3. A pump comprising a housing, a drive member and a cylinder block rotatably mounted in said housing, said cylinder block having bores therein, pistons reciprocably received within said bores, universal joint means connecting said drive member to said cylinder block, a stationary valve block in said housing having inlet and outlet ports therein and a valve member, universal connector means interconnecting said valve member and said cylinder block whereby said valve member is carried by said cylinder block with freedom for universal movement relative thereto, said valve block ports arranged with respect to said valve ports so that fluid to be pumped through said outlet valve block port will be slightly com-

pressed before the outlet valve block port is uncovered, and the uncovering of the inlet valve block port is delayed sufficiently long to allow the fluid to expand slightly before said port is effectively opened.

4. A device as recited in claim 3 in which said inlet and outlet ports comprise arcuate openings to be successively interconnected with said valve ports upon rotation of the cylinder block and valve with respect to the valve block.

5. A pump comprising a housing, a valve block fixed in said housing, and having inlet and outlet ports therein, an axle fixed to said housing and extending through said valve block, a cylinder block rotatably mounted on said axle, said cylinder block having bores therein, piston means reciprocably received within said bores, universal joint means connecting said drive member and said cylinder block, a valve member means whereby said valve member is floatingly carried by said cylinder block with freedom for universal movement relative thereto and having ports connecting bores in said cylinder block with ports in said valve block, sleeve and washer means operatively connecting said bores with said valve ports, spring means operatively associated with said axle and said cylinder block for urging the cylinder block, valve, and valve block into operative engagement, ball means connecting pistons in said bores to said drive member, said balls having a fluid bearing area thereon, means connecting said area with the pressure side of said pistons to transmit a predetermined thrust to said bearing area, and a ring member for retaining said ball bearings in said drive member arranged so as to engage the inner portions of said ball bearings remote from said drive member, and which is responsive to rotation of such drive member to exert a force which increases with the speed of rotation thereof urging said ball bearings into engagement with said drive member.

6. A pump comprising a housing, a drive member and a cylinder block rotatably mounted in said housing, said cylinder block having bores therein, valve means having inlet and outlet ports, universal joint means connecting said drive member with said cylinder block, pistons in said cylinder bores, ball bearing means connecting said pistons with said drive member, a retainer for each ball bearing, spring means for holding said retainers in place for slow rotation of said drive member, each of said retainers being arranged so as to engage the inner portions of said ball bearings remote from said drive member so as to exert increased holding force thereon in response to increased speed of rotation of said drive member.

7. A pump comprising a housing, a drive member and a cylinder block rotatably mounted in said housing, said cylinder block having bores therein, valve means having inlet and outlet ports, universal joint means connecting said drive member with said cylinder block, pistons in said cylinder bores, ball bearing means connecting said pistons with said drive member, said drive member including socket portions for receiving said ball bearings, and a retainer for each ball bearing, said retainers including angle members having openings therein for engaging said balls, and spring and pin means for operatively positioning said angle members to exert a slight holding force upon slow rotation of said drive member, said retainers exerting an increased holding force on said bores in response to increased speed of rotation of said drive member.

8. A pump comprising a housing, a drive member and a cylinder block rotatably mounted in said housing, said cylinder block having bores therein, pistons reciprocably received within said bores, each of said pistons having a recessed portion intermediate its ends for receiving fluid during operation of said pump for centering said piston, universal joint means connecting said drive member to said cylinder block, a stationary valve block in said housing having inlet and outlet ports therein, and a valve member carried by said cylinder block with freedom for universal movement relative thereto, said valve member having ports therein for connecting said cylinder block bores with said valve block ports.

9. A pump comprising a housing, a drive member and a cylinder block rotatably mounted in said housing, said cylinder block having bores therein, piston means reciprocably received within said bores, universal joint means connecting said drive member to said cylinder block, a valve block in said housing, said valve block having inlet and outlet ports therein, a valve member, and means interconnecting said valve member and said cylinder block whereby said valve member is carried thereby with freedom for universal movement with respect thereto and operatively connects the bores in said cylinder block with the ports in said valve block.

10. A pump comprising a housing, a drive member rotatably mounted therein and adapted to be connected to a source of power, a cylinder block in said housing at an angle to said drive member, said cylinder block being provided with a plurality of bores therethrough, piston means reciprocably received within said bores, universal joint means connecting said drive member to said cylinder block, a valve block in said housing, said valve block having inlet and outlet ports therein, a valve member, and universal connector means interconnecting said valve member and said cylinder block whereby said valve member is carried thereby with freedom for universal movement with respect thereto and operatively connects the bores in said cylinder block with the ports in said valve block.

11. A pump comprising a housing, a drive member and a cylinder block rotatably mounted in said housing, said cylinder block having bores therein, pistons reciprocably received within said bores, universal joint means connecting said drive member to said cylinder block, a valve block fixedly mounted in said housing, said valve block having inlet and outlet ports, a valve, universal connector means interconnecting said valve and said cylinder block whereby said valve is carried thereby with freedom for universal movement relative thereto, said valve having bores therein adapted to communicate with said valve block ports, and sleeve means connecting said cylinder block bores with said valve bores whereby said valve operatively connects said cylinder block bores with said valve block ports.

12. A device as recited in claim 11 and further including spring means urging said cylinder block, valve, and valve block into operative engagement.

13. A pump comprising a housing, a drive member and a cylinder block rotatably mounted in said housing, said cylinder block having bores therein, pistons reciprocably received within said bores, universal joint means connecting said drive member to said cylinder block, a valve block in said housing, said valve block having inlet and outlet ports therein, a valve member, universal

connector means interconnecting said valve member and said cylinder block whereby said valve member is floatingly carried by said cylinder block, and spring means urging said cylinder block, valve, and valve block in operative relationship with freedom for universal movement therebetween whereby said valve connects bores in said cylinder block with ports in said valve block.
